DIRECTIVE SENDING SYSTEM.

1,301,644.

Specification of Letters Patent.

Patented Apr. 22, 1919.

Application filed September 13, 1915. Serial No. 50,463.

To all whom it may concern:

Be it known that I, OLIVER ELLSWORTH BUCKLEY, a citizen of the United States, residing at East Orange, in the county of Essex 5 and State of New Jersey, have invented certain new and useful Improvements in Directive Sending Systems, of which the following is a full, clear, concise, and exact description.

10 This invention relates to the art of transmitting signals through space by means of electromagnetic waves.

Its object is to secure a flow of radiant energy from the transmitting station principally in certain definite directions. This object is accomplished by making use of the fact that a number of sources of wave radiation, spaced equally along a line and all oscillating with the same constant frequency, 15 tend to produce by interference a flow of energy principally in one or more definite directions. The power radiated, instead of being approximately uniformly distributed in direction, as in the case of a single source 20 of radiation, will be concentrated in certain definite directions. For example, consider a number of antennæ each capable of radiating waves of a given wave length, uniformly spaced along a straight line and all emitting 25 radiation exactly in synchronism and in phase. Suppose first that the distance between successive antennæ is equal to the wave length. Then a wave starting from one antenna will reach its nearest neighbor 30 just as a wave is starting from that neighbor, so that the two will agree in phase and combine to produce double the effect of either; moreover, at every point along the above mentioned line, extended, the waves from 35 every antenna will agree in phase, and consequently all along this line the amplitude and the energy of the radiation will be maximum. On the other hand, other straight 40 lines drawn outward from the antenna system will in general not be so favorably located, and waves arriving at a given point of such another line from the several antennæ will not agree in phase and will tend 45 to cancel one another. The maximum flow 50 of energy will, therefore, be confined to a few special directions. It is not necessary that the distance between successive antennæ be exactly a wave length; if it is different

from that, however, the direction of maximum energy flow will change and, in fact, 55 the direction of this flow may be adjusted by changing the frequency and consequently the wave length of the emitted radiation. It is, however, necessary that the mutual distances be comparable with the wave length by 60 which is meant, in this specification, that these distances should not be less than perhaps one-tenth the wave length and not more than ten times as large. It is also necessary, in order to secure this effect of directional 65 sending, that the oscillations in the various antennæ shall be exactly in synchronism and that their phase relations shall be invariable. These requirements are usually summarized in the statement that the several sources 70 shall be coherent.

A particular object of this invention is to insure that the radiating antennæ shall be coherent and to obtain this coherence in a practical way by controlling their oscillations from a single low-power source. 75

In order that the novelty of this invention may be appreciated, it is necessary to point out that a number of independent oscillating antennæ, not controlled from one source of power and not otherwise connected with one another, cannot be maintained in synchronism and in phase. Further, it is not practically possible to supply with power from one central source a number of antennæ 85 separated by the distances here contemplated for that would involve transmission of high frequency power of large amount over a distance of several miles. Aside from the loss in transmission over such distances, the 90 mutual capacity of the line wires and their other constants would make it impossible to tune the system sharply to the high frequency desired for radiation. In this invention these difficulties are overcome by locating a power-supplying amplifier at each antenna, all the power to be radiated being derived from its output circuit, and then controlling the operation of these amplifiers from a source of low power oscillations 100 modulated in accordance with the message wave to be sent and centrally located with respect to the several antennæ. In this way the characteristics of the lines from the central source to each antenna have not the same 105 deleterious effect upon the radiation emitted

from the antennæ, for a low efficiency in the transmission of such small amounts of power is not objectionable.

The circuit arrangement of this invention is shown in the drawing. Here 1 represents a generator of high frequency low power oscillations which is shown as an oscillating amplifier of the audion type. Such an amplifier, having its input circuit and its output circuit inductively connected, will oscillate at a frequency determined by the constants of the circuit. In its place, however, any suitable generator of sustained high frequency waves may be used. Transformer 2 connects this generator to the input circuit of the thermionic amplifier 3; into this same circuit are introduced also, by transformer 6, the low frequency oscillations due to variations in resistance of microphone 4 energized by battery 5. The low frequency voltage thus applied to 3 is higher than the high frequency voltage, and its effect is to change the amplifying power of the amplifier 3 so that the high frequency oscillations, appearing in the output circuit of the latter, are modulated in accordance with the low frequency oscillation. This method of modulating high frequency oscillations has been disclosed by van der Bijl in his United States application, Serial No. 46,643, dated August 21, 1915.

By means of transformer 7 the modulated high frequency low power oscillations in the output circuit of 3 are transmitted to a line leading to the various antennæ. The transformers 8 impress these oscillations upon the input circuits of amplifiers 9, which in turn impress the amplified oscillations upon the terminals of the high power amplifiers 10. It will usually be necessary to employ a number of these amplifiers arranged in parallel as shown. (Amplifiers of this type are connected in parallel by connecting together all the filaments, all the grids and all the plates.) The batteries 12 supply direct current to the output circuits of the amplifiers 9, and the choke coils 11 are provided to allow this flow of direct current without affording paths for the high frequency oscillations. The amplifiers 10 energize the two circuits 13, 14, the inductance coils of which are coupled to the coils 15 in antennæ 16. By this arrangement the oscillations in the several antennæ are maintained in exact synchronism and their phase relations are fixed.

Throughout this specification the use of the word "synchronism" implies agreement

with respect to frequency, but not necessarily with respect to phase of two oscillations of similar wave forms.

I wish to point out explicitly that the object of the control circuit is to secure fixed phase relations among the oscillations, but that these need not, and in general will not, be in the same phase; also that the antennæ need not be equally spaced, since the phase of the oscillation in any antenna may be adjusted by any of a number of methods well known to engineers and others familiar with the properties of alternating currents.

What is claimed is:

1. In a system for radio transmission, a plurality of sending antennæ, power-supplying amplifiers associated with each of said antennæ, and a common low power means for controlling the operation of said amplifiers.

2. In a system for radio communication, a plurality of sending antennæ, successive antennæ being separated by a distance suitable for obtaining directive sending, a power supplying amplifier of the unilateral type associated with each of said antennæ, and a central source of low power modulated high frequency oscillations connected with said amplifiers and controlling their operation.

3. In a system for radio transmission, a plurality of sending antennæ, a source of low power high frequency oscillations, means for modulating said high frequency oscillations in accordance with the signals to be transmitted, thermionic amplifiers associated with each of said antennæ, means for impressing the low power high frequency oscillations upon the input circuits of said amplifiers, and means for impressing the resultant high power oscillations upon said antennæ.

4. In a system for radio transmission, a plurality of sending antennæ, a source of low power high frequency oscillations, a circuit containing a telephone transmitter and a source of current therefor, means for modulating said high frequency oscillations in accordance with the oscillations in said circuit, thermionic amplifiers associated with each of said antennæ, means for conductively transmitting said low power oscillations to said amplifiers, and means for impressing the resultant high power oscillations upon said antennæ.

In witness whereof, I hereunto subscribe my name this 10th day of September A. D., 1915.

OLIVER E. BUCKLEY.
